ELLIS G. HOLST, OF LAVOYE, WYOMING.

MINE-TRACK TIE.

Application filed December 13, 1924. Serial No. 755,697.

The purpose of the invention is to provide a metal tie for use particularly in connection with mine tracks, so that rails may be laid quickly and the track dismantled and 5 re-erected with facility.

To this end, the invention comprises the construction and combination of parts of which a preferred embodiment is illustrated in the accompanying drawings, wherein:

10 Figure 1 is a plan view of the tie showing sections of rails mounted in operative positions thereon.

Figure 2 is a front elevational view of the structure of Figure 1.

15 Figure 3 is a perspective view of the clamp or locking member.

The tie proper consists preferably of an inverted channel-shaped bar 1 which may be rolled or pressed, being provided upon its 20 upper face with upstruck integral ears 2 spaced at a proper distance to maintain the requisite separation between the rails 3 with the inner edges of whose flanges the ears engage, overlapping or overhanging the 25 flanges. The tie or body portion 1 is laid and the rails placed thereon and moved into engagement with the ears.

Fastening means are provided to maintain the rails in engagement with the ears 30 and such fastening means comprise the cam-shaped locking members 4, eccentrically pivoted as at 5 and provided with radial projections 6 constituting handles or means by which the locking members may be oscillated 35 or rotated. The locking members are cut away on the rail flange engaging edges, as indicated at 7, to provide ear portions 8 overhanging the rail flanges on the outside.

When the locking members are disposed

so that their handle members 6 lie substantially transversely of the tie, the ear portions 8 overhang the tie flanges and the edges of the locking members abut the edges of the flanges. The rails are thus locked in position on the tie by means of the ears 40 2 and the locking members. When it is desired to dismantle the track, the locking members are swung to a position in which the handle members 6 lie diagonally of the tie and the eccentric mounting of the locking members results in the withdrawal of the rail engaging edges from the flanges so that the rails may then be removed, and they and the ties transported to the point 45 where the track is to be re-erected.

50 The invention having been described, what is claimed as new and useful is:

A rail tie having rail fastening means carried thereby consisting of a rail flange engaging ear upstruck from the tie, and a locking member opposed to said ear and movable into and out of engaging position with the rail flange, said locking member being of disk form and having an eccentric pivotal mounting on the tie and provided, for a portion of its periphery, with a flange which in certain positions of the member overhangs the rail flange, said locking member being provided with a radial extension constituting a handle for effecting its movement 60 and the edge of the disk constituting a cam forcing the rail flange laterally into engagement with said upstruck ear as said locking member is turned in rail locking position.

70 In testimony whereof he affixes his signature.

ELLIS G. HOLST.
